UNITED STATES PATENT OFFICE.

EMILIUS CHRISTIAN FERDINAND BECKER, OF MILLEDGEVILLE, GEORGIA.

BUGGY TOP AND CURTAIN.

No. 928,099.

Specification of Letters Patent.

Patented July 13, 1909.

Application filed September 11, 1908. Serial No. 452,640.

To all whom it may concern:

Be it known that I, EMILIUS CHRISTIAN FERDINAND BECKER, a citizen of the United States, residing at Milledgeville, in the county 5 of Baldwin and State of Georgia, have invented a new and useful Buggy Top and Curtain, of which the following is a specification.

This invention has relation to buggy-top 10 and curtains, and it consists in the novel construction and arrangement of its parts, as hereinafter shown and described.

In buggy tops, as usually constructed and in which supporting bows are employed, the 15 cover is applied to the upper portions of the bows, and that part of the cover which lies over the intermediate or horizontal sections of the bows is generally referred to as the roof or deck, while that part of the cover 20 which lies against the upper substantially vertical portions of the bows is termed the "quarter". A lining is usually applied to the inner and under sides of the bows, and said lining generally terminates substantially 25 at the same level with the lower edges of the quarters, and is provided at its lower edge with a stiffening lace. The space occurring 30 between the bows and between the lower edges of the lace and quarters, is termed the "forks".

It is the object of the present invention to provide side curtains for a buggy top which are adapted to be attached directly to the 35 lower portions of the quarters of the top, and upon the inner sides of the same whereby the lower edges of the quarters will overlap the upper edges of the side curtains.

With this object in view, the present invention consists, primarily, in providing a 40 bridging of flexible material between the lace and the quarter which is secured to both of the said parts by means of stitchings and said bridging material lies between the said parts.

45 Hooks are mounted upon strips of leather, which are secured to the inner sides of the quarters by means of the stitchings above referred to and the stitchings which form the selvage edge of the quarters, and, consequently, the said hooks are located between the quarters and the lace. The valance or the front portion of the cover of the buggy top is provided at its lower sides and front edges with incisions which are adapted to receive 50 the forward portions of the side curtains and which permit the side curtains to be bent

around against the front surfaces of the forward buggy-bow, and upon the front surface of the said bow knobs are located which are adapted to enter eyes provided in the side 60 curtains. The side curtains are also provided at their upper edges with eyelets, which are adapted to receive the hooks which are attached to the inner sides of the quarters, and the lower edge portions of the side curtains 65 are also provided with eyelets which are adapted to receive knobs located upon the sides of the buggy bottom and below the side rails thereof. By such an arrangement it will be seen that means is provided for attaching the side curtains with the cover of 70 the buggy top in such manner that an effectual water-shed is provided, and that no water may run from the roof or the deck of the cover down along the inner surfaces of the 75 side curtains, or along the vertical portions of the bows of the top; nor is it possible that the wheels of the buggy may cast up dirt or mud under the lower edges of the side curtains, inasmuch as they are, when in place, 80 attached to the sides of the body of the buggy and are held in such positions as to effectually shed or ward off any material which may be cast up by the wheels of the 85 vehicle.

Figure 1, is a perspective view of the buggy top and curtains. Fig. 2 is a sectional view of portions of the same.

The buggy top consists of the usual bows 1, upon the upper intermediate portions of 90 which is located the flexible cover 2. The cover 2 consists of the intermediate roof portion or deck, 3, and the side portions or quarters, 4. The lining 5 is located against the inner and under sides of the intermediate 95 portions of the bows 1, and the said lining is provided at its lower edges with the lace 6. The lower edge of the lace 6 is substantially at the same level as the lower edges of the quarters 4. The forward portion of the 100 cover 3 terminates in the usual valance 7, which is provided at its ends and at its forward edges with the slits or incisions 8. The lower edges of the quarters are disconnected from the vertical sides of the bows 1, and the 105 said quarters are connected or tacked to the bows at points about one and one half inches from their lower edges. The lower edges of the quarters 4 are provided with the usual selvage seams 9, and at points substantially 110 in alinement, or thereabouts with the points at which the quarters are connected with the

bows of the top, the said quarters are provided with the horizontally disposed seams or stitchings 10. The strips 11 are secured against the inner sides of the quarters 4 by means of the stitchings 9 and 10, and are located between the bows 1. The hooks 12 are riveted to the strips 11, and are located in the space between the lace 6 and the quarters 4, which space is usually termed the "fork".

10 The bridge material 13 is located in the forks above mentioned, and is secured at one edge to the lace 6, and at its opposite edge to the quarters 4 by means of the stitchings 10, and the intermediate portion of the bridge 15 material 13 lies over the upper ends of the hooks 12. The said material 13 is employed for the purpose of closing the forks above mentioned, and also for bracing the free lower portions of the quarters 4 against the 20 lace 6, which is usually of a stiffening material.

The knobs 14 are located upon the forward sides of the front buggy bow 1, and substantially at the incisions 8, provided in the valance 7. The side curtains 15 are provided at 25 their upper edge portions with the eyelets 16, and at their lower edge portions with the eyelets 17. Knobs 18 are located upon the sides of the body 19 of the buggy and below 30 the side rails thereof.

From the above description, it is obvious that when the eyelets 16 are engaged with the hooks 12 that the upper edges of the side curtains 15 will lie within the forks occurring 35 between the lower edges of the quarters 4 and the lace 6. Consequently, the upper edges of the side curtains 15 will be pocketed, and the lower edges of the quarters will project below the upper edges of the same; consequently, the water that falls upon the roof 40 or deck 3 of the cover cannot enter or pass down along the inner sides of the curtains 15, or against the lower portions of the top bow 1. The forward upper edge portions of the 45 curtains 15 are passed through incisions 8 provided in the valance 7, and the forward eyelets 16 of the curtains 15 are engaged with the knobs 14, and consequently, the forward

portions of the side curtains 15 are bent around the forward bow 1 of the buggy top, 50 and thus a complete water-shed is effected at the forward portion of the buggy top, and in conjunction with the valance section of the cover. The eyelets 17 are engaged with the knobs 18 located upon the body 19 of the 55 buggy, and as the said knobs 18 are located below the side rails of the seat, the lower portions of the side curtains 15 are brought into direct contact with the sides of the body, and any mud or other material cast up by the 60 wheels cannot enter in under the lower edges of the said side curtains. It will also be seen that the leather strips 11 brace the lower portions of the quarters 4 of the cover, and tend to hold the same in proper shape, notwithstanding the fact that the lower edge portions of the said quarters are disconnected from the top bows 1. The said strips also form firm foundations, upon which the hooks 12 are located, and, at the same time, they 65 permit a certain amount of flexion in the material to enable the eyelets 16 to be readily passed over the hooks 12.

Having described my invention, what I claim as new, and desire to secure, by Letters 75 Patent, is:—

A buggy top comprising bows, a cover mounted upon the upper faces of the bows, and a lining mounted upon the lower faces of the bows; a curtain having its upper edge removably assembled with the lower edge of the cover at the inner side of the cover; and a flexible bridging strip disposed between the cover and lining and having its edges assembled with the lower edges of the cover and 85 the lining, the bridging strip being arched intermediate its edges, above the upper edge of the curtain.

In testimony that I claim the foregoing as my own, I have hereto affixed my signature 90 in the presence of two witnesses.

EMILIUS CHRISTIAN FERDINAND BECKER.
